UNITED STATES PATENT OFFICE.

MEADE WILDRICK, OF SAVANNAH, GEORGIA, ASSIGNOR TO W-H KEYLESS LOCK COMPANY, LIMITED, OF HONOLULU, TERRITORY OF HAWAII, A CORPORATION OF THE TERRITORY OF HAWAII.

KEYLESS LOCK AND PERMUTATION WHEEL FOR THE SAME.

Application filed October 27, 1924. Serial No. 746,176.

To all whom it may concern:

Be it known that I, MEADE WILDRICK, a citizen of the United States, residing at Savannah, in the county of Chatham and State of Georgia, have invented certain new and useful Improvements in Keyless Locks and Permutation Wheels for the Same; and I do hereby declare the following to be a full, clear, and exact description of the invention, such as will enable others skilled in the art to which it appertains to make and use the same.

This invention relates to keyless locks and permutation wheels for the same and has for one of its objects to provide a lock of this character and a wheel therefor which will be simple in construction, comparatively inexpensive to manufacture and more efficient in use than those heretofore proposed.

A further object of the invention is to provide a permutation wheel which is particularly adapted for use with keyless locks of the general type shown in the prior co-pending application of Meade Wildrick and Alexander G. Hatch, Serial No. 728,770, filed July 28, 1924, entitled "Keyless lock", and in the patent to Alexander G. Hatch, No. 1,555,969, granted October 6, 1925, and entitled "Improvements in keyless locks".

With the above and other objects in view which will appear as the description proceeds, the invention consists in the novel details of construction and combinations and arrangements of parts more fully hereinafter disclosed and particularly pointed out in the appended claims.

Referring to the accompanying drawings forming a part of this specification, in which like reference characters designate like parts in all the views:

Figure 1 is a rear elevational view, partly broken away, and in section, of one form of lock such as is described and claimed in the said patent of A. G. Hatch, Patent No. 1,555,969, the said lock being provided with one form of permutation wheel constructed in accordance with the present invention;

Fig. 2 is a central vertical sectional view of the parts shown in Fig. 1;

Fig. 3 is an enlarged side elevational view of one of the permutation wheels;

Fig. 4 is a central sectional view through the wheel shown in Fig. 3;

Fig. 5 is an elevational view of a dog retaining disk or member employed in the wheel shown in Figs. 3 and 4;

Fig. 6 is a rear elevational view of a somewhat different type of lock similar to that disclosed in the said Wildrick and Hatch application No. 728,770 with a somewhat modified form of wheel employed therein;

Fig. 7 is a vertical cross-sectional view through the lock shown in Fig. 6; and

Fig. 8 is an enlarged central sectional view through one of the modified forms of wheels and Fig. 9 is a side elevational view of the parts shown in Fig. 8.

Referring more particularly to the Figures 1 to 5 inclusive, the numeral 10 indicates a lock casing in which is suitably mounted a shaft 11. Upon the said shaft is rotatably mounted a plurality of permutation wheels or disks 12, each of which is provided on one of its flat faces with an annular rib 13 provided with a cut-away portion 14 through which the toe 15 of the locking bolt 16 is adapted to pass to lock and unlock the bolt in the manner fully set forth in the said Hatch Patent No. 1,555,969, granted October 6, 1925. The said bolt 16 is slidably mounted for movement transversely of the axis of the shaft 11 and it is adapted to be reciprocated by means of the transverse shaft 17 which carries a finger piece 18 and a disk member 19, which latter is provided with a radial slot 20 receiving the pin or stud 21 carried by the bolt 16. The bolt 16 is slotted as at 22 to accommodate the transverse shaft 17 as will be clear from the drawings.

It is highly desirable in this type of lock that provision be made whereby the combination necessary to control the movements of the bolt may be changed from time to time and to this end the permutation wheels 12 are of a peculiar construction and as is clearly shown in Figs. 3, 4 and 5, these wheels comprise a disk or body member 25 having a hub 26 to receive the shaft 11 and the said member 25 is further provided along the flat face opposite to the annular rib 13 with a second annular rib or projec-

tion 27. This said rib 27 is spaced from the hub 26 so as to provide a recess 28 for the purpose which will appear more fully below and the said recess is normally closed 5 by means of a plate or cross member 29 shown in elevation in Fig. 5.

Loosely mounted upon the disc member 25 and engaging the outer periphery of the same is a ring member 30, the outer circumference of which is provided with suitable indicia 31, as shown in Fig. 1. The said ring member is also provided with a reduced annular hub portion 32 into which the disk or closure member 29 is received when the 10 parts are assembled, as is clearly indicated in Fig. 4. The said hub portion 32 is also provided upon its inner circumference with a plurality of arcuately spaced notches or recesses 34 which are adapted to receive the 15 nose of the slideable dog 35 which dog is mounted in a slot or cut-away portion 36 of the annular rib 27 of the disk member 25. The inner end of the dog 35 projects slightly beyond the inner circumference of 20 the rib 27 and is engaged by the spring 37 which is mounted within the recess 28, as clearly shown in Figs. 3 and 4. The dog 35 is also provided with an angular pin or extension 38 which projects outwardly through 25 a slot 39 formed in the disk member 29, so that said dog may be manually manipulated as will appear more fully below. The disk member 29 may be retained in position by means of suitable screws 40 passing there- 30 through and engaging in the disk member 25.

Assuming the parts to be in the position shown in Figs. 3 and 4, should it be desired to change the combination, it is only necessary to move the dog 35 radially inwardly by means of the extension 38, so as to disengage the nose of the said dog from the recess 34 which it happens to be occupying, whereupon the ring member 30 is unlocked from engagement with the body or disk member 25 and may be freely rotated thereon. The relative positions of the two members may therefore be changed and when the desired position has been reached the dog 35 may be released whereupon the spring 37 will again force its nose into one of the recesses 34 thereby efficiently locking the parts together again.

In some forms of lock it may be possible to accomplish movements of the dog 35 directly by means of the fingers, but it is preferred to provide means upon the lock casing 10 whereby this may be effectively accomplished without access being had to the interior of the casing. To this end there is provided upon the rear member 41 of the casing a boss 42 which is provided with a bore 43 through which passes a push member 44. The said member is provided with a collar or enlargement 45 behind which is mounted a coiled spring 46 which spring

normally urges the said push member 44 toward the right, as viewed in Fig. 2.

The parts are so designed and constructed that the inner end of the push member 44 is preferably beveled, as indicated at 48, in close proximity to the angular extension 38 of the dog 35 and when the member 44 is pushed inwardly the beveled end 48 of the said member will engage the said extension 38 to force the dog 35 out of its recess 34. With the parts held in this position, it is an easy matter to rotate the ring member 30 from the front of the lock as will be clear from Fig. 2 until the new position of the said member has been attained, whereupon by releasing the push member 44, the parts will be restored to the positions shown in the drawings and the ring member 30 efficiently locked to the body member 25.

Referring now to the modified form of wheel shown in Figs. 6 to 9 inclusive which is particularly adapted for use in the form of lock shown in the co-pending application of Meade Wildrick and A. G. Hatch, No. 728,770, it will be noted that this lock comprises a casing 50 in which is slidably mounted a bolt 51 having a stud or shaft 52 rigid therewith and upon which is mounted the permutation wheels 53. As is clearly and fully disclosed in the said Wildrick and Hatch application, this form of lock operates through the movement of the bolt 51, the stud 52 of which is provided with suitable lugs or projections 54 which are adapted to move through axial keyways 55 formed in the permutation wheels.

These wheels, as is shown in detail in Figs. 8 and 9, comprise the body members 56, upon the exterior circumference of which is loosely mounted the indicia bearing ring member 57. The said body member 56 is also provided with a reduced hub 58, the exterior circumference of which is provided with a plurality of arcuately spaced notches or recesses 59, the member 57 is also provided with a recess 60 in which is mounted an L-shaped dog 61 which is pivoted as at 62 to the said member 57 and the angular extension 63 of which is positioned to engage the said notches 59 as will be clear from Figs. 8 and 9. The said dog 61 is also provided with a pin or extension 64 which projects outwardly through a slot 65 formed in the retaining ring 66 whereby movements of the said dog 61 may be controlled. A suitable flat spring 67 is positioned within the recess 60 behind said dog 61 and normally urges its toe 63 into an engagement with the notches 59.

The operation of shifting the combination with this form of wheel is similar to that already described in connection with the previous form, except, of course, that the dog 61 oscillates about its pivot 62 to engage and disengage the notches 59. These said

notches also serve as detent notches for receiving a portion of the detent springs 69, which are carried by the lock casing 50, see Fig. 7, whereby the wheels are held in 5 any desired position.

A suitable push member 70 may also be provided in this form of lock for releasing the dog from engagement with the notches 59 which member may be of a construction 10 similar to that already described.

It is obvious that those skilled in the art 15 may vary the details of construction as well as the arrangements of parts without departing from the spirit of the invention and therefore it is not wished to be limited to the above disclosure except as may be required by the claims.

What is claimed is:

1. A lock comprising a casing, a lock 20 mechanism including a plurality of independently settable permutation tumblers mounted in said casing, each of said tumblers comprising a concealed lock-controlling element and an indicia-bearing element exposed for manipulation through a slot in said casing, couplings normally preventing relative combination changing movements between the composite elements of said tumblers, and coupling-disabling means accessible from the exterior of the assembled lock whereby said couplings may be rendered ineffective, thereby permitting said indicia-bearing to be directly and independently moved to effect a change in the combination of the lock while said lock-controlling elements are held fast.

2. A lock comprising a casing, a lock 40 mechanism including a plurality of permutation tumblers mounted in said casing, each of said tumblers comprising a concealed lock-controlling element and an indicia-bearing element exposed for manipulation through a slot in said casing, couplings normally preventing relative movement between the composite elements of said tumblers, and indi-

vidual disabling devices accessible from the exterior of the assembled lock whereby the respective couplings may be selectively rendered ineffective, thereby permitting the indicia-bearing element of any of said tumblers to be moved to effect a change in the combination of the lock while its lock-controlling element is held fast. 50

3. A permutation wheel for keyless locks 55 comprising a lock-controlling element having a recess at one side, an indicia-bearing element extending about said lock-controlling element, a slotted disk fitted within said indicia-bearing element for closing said recess of the lock-controlling element, and a yieldably-engaged coupling in said recess for binding the composite elements of the wheel together and against relative rotation, said coupling having a part projecting 60 slidably through said slotted disk for manipulation from the exterior of said recess.

4. A lock comprising a casing, a lock 70 mechanism including a locking bolt movably mounted in the casing, a plurality of permutation tumblers in said casing, each comprising a lock-controlling element having a part at one side for cooperation with said bolt and a recess at its opposite side, an indicia-bearing element extending about said lock controlling element, a slotted plate fitted within said indicia-bearing element for closing said recess of the lock-controlling element, a yieldably-engaged coupling in 75 said recess for binding the composite elements of the tumbler together and against 80 relative rotation, said coupling having a part projecting through said slotted plate but concealed within the casing, and independent means mounted through the casing for operation on the exterior of the casing 85 whereby to engage said parts of the couplings and disengage said couplings to permit of relative rotation in the tumber elements.

MEADE WILDRICK.
